UNITED STATES PATENT OFFICE.

GEORGE GARTLING, OF LOS ANGELES, CALIFORNIA.

ROTARY WELL-DRILLING BIT.

Application filed March 28, 1922. Serial No. 547,410.

An object of this invention is to provide a rotary well drilling bit, the cutters of which can be economically made of high grade steel and can be re-sharpened with ease.

The invention is broadly new, basic and pioneer in that I provide a cutter body adapted to rotate on a central axis and having gains on its front sides and clamping plates therefor that are adapted to clamp the shanks of detachable cutters. Said front sides and clamping plates are recessed to hold the shanks non-rotatably in clamping slots.

Objects of the invention are simplicity, strength of construction, ease of assembling and disassembling and security against loss of the cutters.

An object is to so construct the stock as to afford maximum strength and to afford maximum convenience of assembly and disassembly.

Another object is to so construct and arrange the cutters as to secure the most rapid cutting. An advantage gained with this invention arises from application of the cutters at an acute angle to the surface to be cut so as to cut most efficiently.

Other objects, advantages and features of invention may appear from the accompanying drawing, the subjoined detail description and the appended claims.

The accompanying drawing illustrates the invention.

Figure 1 is an elevation of a rotary drill bit constructed in accordance with this invention.

Fig. 2 is a bottom view of the bit shown in Fig. 1.

Fig. 3 is a bottom view of the stock and clamping plates (Figs. 1 and 2) secured together by bolts and omitting the cutters.

Fig. 4 is a section on line α^4 , Fig. 2.

Fig. 5 is a section on line α^5 , Fig. 4.

Fig. 6 is an edge view of the bit shown in Fig. 1.

Fig. 7 is a section on line α^7 , Fig. 1.

Fig. 8 is a top view of one of the cutters.

Fig. 9 is a side view of one of the cutters.

The bit is provided at its upper end with a taper screw 1, and a stock abutting cylindrical collar 2 beneath which is the body 3 extending endwise from and laterally beyond said collar. The bit may be constructed to turn from right to left or may be re-

versely constructed, as desired. A bit adapted to turn from right to left is shown in the drawings. Each face of the bit body 3 comprises a front side or an advancing face a and a back side or retreating face b reversely arranged on the opposite sides of the medial plane c of the bit, such plane c extends transversely through the bit at right angles to the advancing face a or retreating face b .

The advancing face a on each side of the medial plane c is provided with a gain 4 cut about half-way through the body 3, and the floor of said gain is provided with a desired number of eccentric semi-hexagonal shank-receiving grooves or seats 5 that are parallel with the medial plane c ; and into each gain there is fitted a clamping plate or piece 6 provided with like grooves 5', co-operating with the grooves 5. The eccentric cutters are chisels 7 having shanks 8 adapted to fit the grooves 5 and 5' and are of such diameter as to space the floor of the gain and the inside wall of the clamping plate apart as at 9 sufficiently to allow the shanks to be firmly and non-rotatably clamped between the clamping plate and the floor of the gain when the bolts 10 are tightened.

Said bolts are shown as provided with nuts 11 and washers 12. The shanks 8 are shown as hexagonal in form and the grooves 5 and 5' are semi-hexagonal in form so that the clamped cutters will be non-rotatable and may be easily removed and replaced when the clamp pieces 6 are removed or sufficiently loosened for the purpose. The bolts 10 are applied in such number and arrangement as to enable the workman to tightly clamp the parts together and to positively fix the cutters.

The bolts may be provided with any lock-nut or other suitable means not shown for preventing the nuts from unscrewing.

The tips or chisels 7 of the cutters are preferably bent forward in the direction of rotation as indicated in Figs. 2, 5, 6, 8 and 9, and may be staggered as to a horizontal plane as indicated in Figs. 1, and 4. That is each successive inwardly spaced cutter is arranged with its tip above the tip of the adjacent cutter.

In practice the cutters and clamping plates are applied and withdrawn as desired and when the cutters become worn they will be removed, upset and sharpened. This is done

from time to time until the shank is too short for practical use, when a new cutter may be supplied.

In the fish-tail form of bit shown in Figs. 6 1 and 4 the staggered arrangement of cutters enables the tool to cut more rapidly as is well known to the art. It is understood, however, other arrangements of cutters may be made without departing from the spirit 10 of this invention.

The usual water courses 13 through the taper screw and collar open into the medial groove 14 so as to direct water supplied from a source not shown to the center of the 15 cut.

The body of the bit below the taper thread and collar stock comprises two shoulders 15, a central stem 16, and two backings 17 and 17' integral with said shoulders and stem 20 and in offset or staggered relation to each other so that the pressure to drive the cutters is well supported and the tool is compact and strong.

The floors of the gains which are the front 25 faces of the backings 17 and 17' are practically in the same vertical plane and are radial to the axis of rotation and the depth of shank seats 5 and 5' are somewhat less than half the diameter of the shanks so as to 30 insure a tight frictional grip on the shanks:

I claim:

1. A rotary well drilling bit comprising a body having gains on its forward faces; clamping pieces in said gains; cutters having 35 shanks between the clamping pieces and floor of the gains; and means to secure the cutter shanks between the clamping pieces and the floor of the gains.

2. A rotary well drilling bit having faces 40 and comprising a body having gains on opposite sides of a medial plane extending transversely through the bit at right angles to said faces; clamping pieces in said gains; cutters having shanks; and means adapted 45 to non-rotatably hold said shanks between said clamping pieces and gains, said gains being practically in the same vertical plane and radial to the axis of rotation.

3. A rotary well drilling bit comprising a body having gains on its forward faces; clamping pieces in said gains; cutters having 50 shanks between the clamping pieces and floor

of the gains; and means to secure the cutter shanks between the clamping pieces and the floor of the gains, said cutters having cutting tips bent forward and extending aslant 55 forwardly and downwardly from the cutter shanks.

4. A rotary well drilling bit comprising a body having on its forward faces, gains 60 the floors of which are provided with grooves; clamping plates fitted in said gains and provided with grooves adapted to cooperate with the grooves in said gains; cutters having shanks; and means adapted to 65 non-rotatably clamp said cutter shanks in said grooves.

5. A rotary well drilling bit comprising a body having gains the floors of which are provided with semi-hexagonal grooves; 70 clamping plates fitted in said gains and provided with semi-hexagonal grooves adapted to cooperate with the grooves in said gains; cutters having hexagonal shanks; and means adapted to 75 clamp said cutter shanks in said grooves.

6. The integral rotary drill bit stock for detachable cutters and clamping means therefor substantially as set forth said stock comprising a taper thread and a collar, 80 shoulders, stem and backings; said backings being in offset relation to each other to accommodate said clamping means so as to apply power at the rear of cutter shanks fixed on opposite sides of the stem, when 85 the stem is rotated in the appropriate direction substantially as set forth.

7. A rotary well drilling bit comprising a body having gains on its forward faces; clamping pieces in said gains; cutters having 90 shanks between the clamping pieces and floor of the gains; and means to secure the cutter shanks between the clamping pieces and the floor of the gains, said cutters having cutting tips bent forward and extending aslant 95 forwardly and downwardly from the cutter shanks; said cutter being arranged with the tips of each successive inwardly spaced cutter above the tip of the adjacent cutters.

In testimony whereof, I have hereunto set 100 my hand at Los Angeles, California, this 20th day of March, 1922.

GEORGE GARTLING.
